UNITED STATES PATENT OFFICE.

AXEL VERNER OSTERBERG, OF FREMONT, OHIO.

TOY.

1,296,844.

Specification of Letters Patent. Patented Mar. 11, 1919.

Application filed March 14, 1917. Serial No. 154,657.

To all whom it may concern:

Be it known that I, AXEL VERNER OSTERBERG, a citizen of the United States, residing at Fremont, in the county of Sandusky and 5 State of Ohio, have invented certain new and useful Improvements in Toys; and I do declare the following to be a full, clear, and exact description of the invention, such as will enable others skilled in the art to which 10 it appertains to make and use the same, reference being had to the accompanying drawings, and to the figures of reference marked thereon, which form a part of this specification.

15 My invention relates to and its object is to provide a toy in which a slight explosion discharges with a report an arrow or similar projectile.

20 My invention is illustrated in the single figure of the accompanying drawing, which is a side-elevation of my device, with a portion of the cylinder, hereinafter referred to, broken away to show the internal arrangement.

25 In the drawing, 1 is a cylindrical shell closed at one end, composed of any suitable material, as for instance, drawn brass. 2 is a cork or stopper which fits closely into the open end of the cylinder 1. Firmly fixed in 30 the cork or stopper is one end of the shaft of an arrow 3, carrying at its outer end a feather or similar appendage 4, to steady the forward end of the shaft in its flight. 5 is a weight or slug of lead or other suitable 35 metal, shorter than and capable of movement in the space between the bottom of the cylinder and the inner end of the cork. 6 is an explosive percussion-disk, of paper, such as is used with toy pistols and the like.

40 The percussion-disk is dropped into the

mouth of the cylinder 1, the slug is slipped onto the top of the disk, the cork is pushed tightly into the mouth of the cylinder, with its arrow projecting outwardly. The device is now ready for operation. The boy throws 45 the cylinder thus loaded up into the air as far as he can. When the bottom of the cylinder strikes the ground, the percussion-disk is exploded by the impact of the slug, the resulting gases discharging the cork with a 50 report and shooting the arrow into the air. The slug is usually thrown from the cylinder but a short distance and is readily found and may be used indefinitely, the only supplies required being the cheap percussion- 55 disks.

Having described my invention, what I claim and desire to secure by Letters Patent, is—

1. A toy comprising a cylinder closed at 60 one end, a stopper for the open mouth of the cylinder, an elongated feathered shaft connected with the stopper, and a metal slug movable between the bottom of the cylinder and the inner end of the stopper. 65

2. A toy comprising a cylinder closed at 70 one end, a stopper for the open mouth of the cylinder, an elongated feathered shaft connected with the stopper, and a metal slug movable between the bottom of a cylinder and the inner end of the stopper, combined with an explosive percussion-member interposed between the bottom of the cylinder and said slug.

In testimony whereof I affix my signature 75 in presence of two witnesses.

AXEL VERNER OSTERBERG.
